UNITED STATES PATENT OFFICE.

JOHN C. TITUS, OF MARION, OHIO.

STEAM-BOILER.

SPECIFICATION forming part of Letters Patent No. 273,640, dated March 6, 1883.

Application filed March 16, 1882. (No model.)

To all whom it may concern:

Be it known that I, JOHN C. TITUS, of Marion, in the county of Marion, and in the State of Ohio, have invented certain new and useful 5 Improvements in Steam-Boilers; and I do hereby declare that the following is a full, clear, and exact description thereof, reference being had to the accompanying drawings, and to the letters of reference marked thereon, making a 10 part of this specification, in which—

Figure 1 is a front end elevation of my improved steam-boiler with one lid of the smoke-box raised to expose the return-flues. Fig. 2 is a vertical cross-section through the boiler, 15 taken in the plane indicated by dotted lines x x , Figs. 3 and 4. Fig. 3 is a diametrical section through the boiler in the vertical plane indicated by dotted lines y y on Fig. 1. Fig. 4 is a side elevation of the boiler.

Similar letters of reference indicate corresponding parts.

This invention relates to an improvement on steam-boilers which are specially designed for portable engines, steam-tugs, and the like, 25 but which is also useful for road or farm locomotives having boilers of the kind denominated "return-flue" boilers.

My invention relates to steam-boilers of the horizontal or return-flue kind; and the nature 30 of my invention consists in certain novel features, which will be fully understood from the following description, when taken in connection with the annexed drawings.

A designates the dome or vertical section of 35 the boiler, and B the horizontal portion or body of the boiler.

The letter G designates a series of two or 40 more vertical stays or braces having a firm and strong connection with the crown-sheet of the dome A and with the boiler, the function 45 of which is to insure a reliable and unyielding union between the dome and boiler. The said stays or braces are connected with the crown of the dome or chamber A by means of the transverse bars A', which are themselves riveted to the crown.

B' designates the main fire-flue and combustion-chamber, in which is the grate B².

C are the return fire-flues; D, the smoke-box or combustion-chamber at the end of the boiler, through which the products pass on their way to the return-flues, which latter pass forward and communicate with the uptake E,

as indicated by the course of the arrows on Fig. 3.

As ordinarily constructed the water-line in 55 this class of horizontal steam-boilers is a short distance above the crown of the main fire-flue B', and the small dome on the top of the boiler-shell is used exclusively for receiving the 60 steam.

The advantages of a boiler constructed substantially in the manner above described are to raise the water-line above the horizontal part B of the boiler into the vertical part A 65 thereof, so that as either end of the boiler is raised or lowered, as in going up or down grade, no part of the fire-surface is left bare of water. I thus avoid the danger of overheating any part, and consequently there will 70 be no tendency to explosion from softening of plates and over-pressure.

It is obvious that by raising the water-line above the highest point of the section B a 75 larger number of return-flues, C, can be arranged in the boiler, and the heating capacity thereof greatly augmented.

By arranging the flues as shown and extending the water-line up into the enlarged dome A a larger body of water can be carried in a 80 boiler of a given size to absorb and retain the heat than can be carried in the well-known return-flue boilers.

If desired, three or more of the return-flues (marked C' in Fig. 2) may be omitted from 85 one or both sides of the boiler, for the purpose of insuring better circulation.

Having described my invention, I claim—

The combination, in a steam-boiler, of the outer shell having its upper portion perforated 90 and provided with a cylindrical water-chamber having strengthening-bars attached to its crown and united to the shell by rivets and braces or stays, with the inner shell secured to the outer and provided with grate-bars located therein, and return-flues running there-through and communicating with the uptake, 95 substantially as shown and described.

In testimony whereof I affix my signature, in presence of two witnesses, this 5th day of December, 1881.

JOHN C. TITUS.

Witnesses:

JOHN E. DAVIDS,
LIBBIE M. DAVIDS.
